UNITED STATES PATENT OFFICE.

ERNEST L. FARROW AND CHARLES R. BARKER, OF CLEVELAND, OHIO, ASSIGNEES TO
THE CLEVELAND WIRE SPRING COMPANY, OF CLEVELAND, OHIO, A CORPORATION.

BED-SPRING.

1,143,179.

Specification of Letters Patent. Patented June 15, 1915.

Application filed April 27, 1914. Serial No. 834,765.

To all whom it may concern:

Be it known that we, ERNEST L. FARROW and CHARLES R. BARKER, citizens of the United States, residing at Cleveland, in the county of Cuyahoga and State of Ohio, have invented certain new and useful Improvements in Bed-Springs, of which the following is a specification.

This invention appertains to bed springs and the invention consists in the construction substantially as shown and described and particularly pointed out in the claims.

In the accompanying drawings, Figure 1 is a plan view of the invention omitting a few springs in one corner of the view. Fig. 2 is a side elevation and Fig. 3 is an end elevation. Fig. 4 is a view corresponding to Fig. 2 in the parts shown by omitting the outer frame. Fig. 5 is an edge elevation 20 of the said outer frame, seen in plan in Fig. 1. Sheet 2, Fig. 6 is a bottom view of the inner frame and its springs. Fig. 7 is a plan view, considerably enlarged, of one corner of the complete structure and comprising portions of both frames. Fig. 8 is a section view and elevation of the portion of the structure seen in Fig. 7.

The complete article of manufacture as thus shown comprises an outer or main frame A of skeleton form and an inner frame B positioned bodily within frame A and carrying spiral springs 2, and the said frames are independent and separable as members, so that the frame B can be detached and bodily removed from the frame A when desired. The outer frame A is constructed with two side rails, pipes or tubes 3 and two end cross-bars 4 which are mounted upon arms 5 at ends of the side rails 3. 40 The said ends 4 are preferably of angle iron and rigidly secured on the outer extremities of the arms 5 which are preferably curved to the segment of a circle and extend upward and outward endwise from the side tubes 3 on which they are socketed, as seen at 6, Figs. 1 and 7, or otherwise firmly engaged on the ends of said tubes. The elevation and location of the cross-bars 4 in respect to the longitudinal side rails 3 is seen 45 particularly in Fig. 2 and also in Fig. 8, which is about half size, and the inner frame B is suspended by four springs 7 in the same horizontal plane as the side bars and is of substantially the same length thereas.

55 The invention resides primarily in the

two frames A and B and the means by which they are combined and made complete as an article of merchandise, and the spiral springs 7 by which frame B is suspended from frame A constitute an important part 60 of the complete invention. Said springs 7 are inclined to substantially the same angle as the arms 5, whereby end swaying of the frame B is eliminated, and these springs are mainly depended upon to support and carry 65 the bed frame B with all its possible burden of springs and occupants. However, horizontal springs 8 are also employed, which connect a wire mesh 9 over the springs 2 with the cross-bars 4 at frequent 70 intervals, and of course said springs 8 also contribute to take care of the load upon the bed bottom, but these springs being horizontal are not particularly active as vertical supports. The wire mesh 9 is interwoven 75 with the springs 2 and bordered by a comparatively heavy wire 10 to which the inner ends of the horizontal springs 8 are attached, and the outer ends of springs 8 are detachably secured within holes in cross-bars 4. The spiral supporting springs 2 rest on angle-iron cross-bars 12 connecting the longitudinal side bars 13 of frame B, and the suspensory springs 7 are connected at their bottom ends with the extremities of 80 said side bars 13.

The springs 7 are necessarily of considerable strength and under constant tension to exert uplift of the bed frame B relatively to the wire mesh 9, and the effect is to compress the spiral springs 2 and raise and bow the middle portion of the spring bottom, and a further effect is to stretch the horizontal springs 8 and the wire mesh 9. The side tubes A also are somewhat bowed upward 85 in their middle as compared with the ends, Fig. 5, for bracing effect.

The spiral springs 2 and wire mesh 9 and the border wire 10 and the inner frame B on which the springs 2 are supported comprise a spring bed bottom or mattress, which is spring supported in turn by the springs 7 and 8 attached to the frame A; and the latter frame is adapted to fit within and rest upon the side rails of a bed. The complete bed spring as shown and described is exceptionally strong and durable, and is capable of uniformly distributing the 100 weights and strains to which it may be subjected while permitting unequal loads at 105 110

separate points thereon to be cushioned independently.

What we claim is:

1. In a bed spring, an outer skeleton frame having ends supported on a plane above the sides thereof by means of rigid arms, a spring bottom and a carrying frame therefor within said outer frame and suspensory springs connecting the corners of said carrying frame with said ends.
2. A skeleton main frame having raised ends, an inner frame suspended by springs at its four corners from the corners of said skeleton frame, and a spring mattress mounted on said inner frame having a wire woven top connected at intervals by means of springs with the ends of said outer frame.
3. In a bed spring, a rigid outer frame comprising ends raised in respect to the sides thereof and outward therefrom and outwardly projecting arms at an inclina-

tion supporting said ends from the sides of the frame, in combination with a spring bed bottom within said outer frame and springs at the corners thereof suspending the same from the said raised ends. 25

4. In a bed spring, a main frame having ends raised and projected beyond the sides thereof on a plane above said sides and inclined arms supporting said ends, in combination with a bed bottom comprising a rigid frame within said main frame, and a spring at each corner thereof suspending said frame from the ends of said main frame. 30

In testimony whereof we affix our signatures in presence of two witnesses. 35

ERNEST L. FARROW.
CHARLES R. BARKER.
